TABLE

Nils Erik Strinning, Saltsjobaden, near
Stockholm, Sweden

Application April 14, 1953, Serial No. 24,502

Term of patent 14 years

(Cl. D33—14)

To all whom it may concern:

Be it known that I, Nils Erik Strinning, a citizen of the Kingdom of Sweden, residing at Brovagen 10, Saltsjobaden, near Stockholm, Sweden, have invented a new, original, and ornamental Design for a Table, of which the following is a specification, reference being had to the accompanying drawing, forming part thereof.

The single figure is a perspective view of a table showing my new design.

I claim:

The ornamental design for a table, substantially as shown and described.
